UNITED STATES PATENT OFFICE

92,395

DESIGN FOR A PLATE FOR DANCING SHOES

Morris A. Feinstein, Chicago, Ill., assignor to Aza
Mfg Co., Chicago, Ill., a corporation of Illinois

Application March 31, 1934, Serial No. 51,276

Term of patent 3½ years

To all whom it may concern:

Be it known that I, MORRIS A. FEINSTEIN, a citizen of the United States, residing at Chicago, county of Cook and State of Illinois, have invented a new, original, and ornamental Design for a Plate for Dancing Shoes, of which the following is a specification, reference being had to the accompanying drawing forming a part thereof.

On the drawing,

The figure is a perspective view of a plate for dancing shoes showing my new design.

I claim:

The ornamental design for a plate for dancing shoes, substantially as shown.

MORRIS A. FEINSTEIN.
